DRAPERY CORD LATCH

Orville T. Stall, Whittier, Calif.

Application December 30, 1957, Serial No. 49,068

Term of patent 14 years

(Cl. D21—1)

Fig. 1 is a bottom view of the drapery cord latch provided by the instant invention;

Fig. 2 is an end elevational view taken as indicated by line 2—2 on Fig. 1;

Fig. 3 is a side elevational view taken as indicated by line 3—3 on Fig. 1;

Fig. 4 is a side elevational view taken as indicated by line 4—4 on Fig. 1;

Fig. 5 is an end elevational view taken as indicated by line 5—5 on Fig. 1; and,

Fig. 6 is a top view thereof, taken as indicated by line 6—6 on Fig. 4.

I claim:

The ornamental design for a drapery cord latch, substantially as shown.
